UNITED STATES PATENT OFFICE.

JOHN W. MEAKER, OF PHILADELPHIA, PENNSYLVANIA.

BUCKLE.

SPECIFICATION forming part of Letters Patent No. 308,915, dated December 9, 1884.

Application filed December 3, 1883. (No model.)

To all whom it may concern:

Be it known that I, JOHN W. MEAKER, a citizen of the United States, and a resident of the city and county of Philadelphia, State of Pennsylvania, have invented a new and useful Improvement in Buckles, which improvement is fully set forth in the following specification and accompanying drawings, in which—

Figure 1 is a top or plan view of a buckle embodying my invention, a strap being attached. Fig. 2 is a longitudinal section thereof. Figs. 3 and 4 are sectional views of modifications. Fig. 5 is a side elevation of a buckle embodying my invention. Fig. 6 is a view of 15 a part of harness having my invention applied to it.

Similar letters of reference indicate corresponding parts in the several figures.

My invention consists of a buckle formed of 20 a back plate having loops, both of sheet metal, and a stud or post, the strap being adapted to be fitted to said stud and retained thereon by the loops, thus securely connecting the strap and buckle.

25 It also consists of certain other details of construction, as will be hereinafter fully set forth.

Referring to the drawings, A represents a buckle, consisting of a plate, *a*, loops *b*, and 30 stud *c*, said plate and loops being formed of sheet metal, and said studs *c* of suitable metal connected with said plate, the loops being at the ends of the plate and the stud rising from the plate intermediate of the loops. Rising 35 from the plate under either loop is a stud, *d*, which is shorter than the stud *c*. The strap to be buckled has one end passed through the proper loop and engaged with the stud *d*. The other end of the strap or another length of 40 strap is then inserted through the loops and engaged with the stud *c*, it being noticed that the short stud *d* does not project beyond the inner or lower strap, whereby the other strap may be passed over the short stud between the 45 same and the overhanging loop thereof and shifted without obstruction. As the straps are connected with the studs and the loops prevent rising of the straps, they are firmly and securely buckled.

50 Rising from the sides of the plate *a* are flanges *a'*, which are of such height as to embrace the sides of the lower or inner strap on the buckle.

When the strap is to be unbuckled the fingers are applied to the buckle, so as to bow or bend outwardly the upper or outer strap, thus disengaging it from the stud *c*, it being noticed that the flanges *a'* serve as guards for preventing the fingers reaching the lower or inner strap and bowing the same and jamming the two straps, consequently the upper or outer 60 strap may be readily slipped through the loop or loops and removed. Then the lower strap may be bowed and disengaged from its stud and conveniently removed, the strap or straps thus being unbuckled. The plate extends the 65 entire length of the buckle, so that its ends are coincident with the outer ends of the loops *b*. By this provision the bending of the portions of the strap outside of the buckle does not affect the portions within the buckle and 70 throw the same off from the studs; hence the security of connection of the strap or straps with the buckle is assured.

B represents a slide for the two lengths of straps, or a length of one strap and end of the 75 other, to prevent flapping or separation of the straps at contiguous places, said slide being in the form of a loop, *b*, from the back plate, *a*, of which rises a stud, *c*, which is of such height or length as to engage with only the 80 lower or inner strap, leaving the upper or outer strap free to pass the same. When the slide is adjusted its stud enters the proper opening in the lower or inner strap or length then being inserted, or if inserted, moving 85 along in the slide without interference of the stud *c* until it occupies its proper position, when it covers the end of the stud, preventing disengagement of the other strap and retaining 90 the slide on the straps.

In Fig. 3 I show the buckle duplicated, with loops and studs on opposite sides, and in Fig. 4 I attach a loop on the back of the buckle (shown in Fig. 1) for the purposes of tugs, names, &c. In Fig. 6 the buckle is illustrated as applied to a blind, the back-plate 95 loops in this case being elongated.

In order to increase the hold of the strap on the stud to which it is affixed, the outer end of the stud is bifurcated or spread, whereby, 100 when the strap is fitted thereon, the bifurcation forms in a measure a key, preventing accidental separation of the strap from the stud.

In manufacturing the buckle, I construct

the same of sheet metal cut into proper shape and turned up, thus forming the end loops and slide-flanges. This reduces the cost of making the buckle, owing to the saving of time and labor, and as the loops need not close at top, there is also a saving of material.

Having thus described my invention, what I claim as new, and desire to secure by Letters Patent, is—

- 10 1. An improved buckle, formed of a back plate and a loop or loops of sheet metal, and a stud or studs connected with said plate, substantially as and for the purpose set forth.
- 15 2. A buckle formed of a back plate, a loop, and studs of different lengths, substantially as and for the purpose set forth.
3. A buckle formed of a back plate, a loop,

and stud, the outer end of the latter being bifurcated, substantially as and for the purpose set forth.

20 4. An improved buckle, formed of a back plate, a loop or loops and side flanges of sheet metal, and a stud or studs connected with said plate, substantially as and for the purpose set forth.

25 5. An improved buckle, formed of a back plate and a loop or loops of sheet metal, and a stud or studs and loop or loops connected with the back plate on opposite sides thereof, substantially as and for the purpose set forth. 30

J. W. MEAKER.
